UNITED STATES PATENT OFFICE.

BURT A. PETERSON, OF ROCKFORD, ILLINOIS, ASSIGNOR TO HOWARD D. COLMAN,
LUTHER L. MILLER, AND HARRY A. SEVERSON, COPARTNERS DOING BUSINESS
AT ROCKFORD, ILLINOIS, AS BARBER-COLMAN COMPANY.

YARN-CARRIER SUPPORT.

1,274,442.

Specification of Letters Patent. Patented Aug. 6, 1918.

Application filed April 23, 1917. Serial No. 163,814.

To all whom it may concern:

Be it known that I, BURT A. PETERSON, a citizen of the United States, residing at Rockford, in the county of Winnebago and State of Illinois, have invented certain new and useful Improvements in Yarn-Carrier Supports, of which the following is a specification.

In application Serial No. 781,919, filed July 30, 1913, by Howard D. Colman, is shown a warper creel comprising sections therein termed "tridents." Each trident comprises a base to which is fixed three parallel spindles, each spindle being of sufficient length to support four yarn masses termed "cheeses." The tridents are adapted to be used at the spooler or winder as receptacles or supports for the yarn masses when removed from the spooler or winder, and are adapted to be transported to and placed upon the framework of the warper creel.

In order that the cheeses may be rewound upon the section beam of the warper at high speed and under low tension, it is necessary that the cheeses shall be so supported by the tridents as to rotate with the least possible friction. It also is very important that the pivotal supports or bearings of the cheeses in the tridents shall be of such nature as to require no attention in the way of adjustment or lubrication during relatively long periods of use.

One of the objects of this invention is to improve the trident shown in said application Serial No. 781,919 with a view to reducing friction and minimizing the attention necessary to maintain the pivotal supports of the cheeses in satisfactory working condition. This object has been attained by providing ball bearings for the trident rollers and by providing means for efficiently lubricating the bearings, the lubricating means being of such character as not to require replenishment of oil or other attention during relatively long periods of use.

When the tridents are in use at the winder or are being transported from the winder to the warper creel frame, the tridents stand upon their bases with the spindles in upright position. When in such position the yarn carriers on a given spindle rest upon one another. When the tridents are in use in the creel, the spindles occupy a horizontal position and each yarn carrier should be sup-

ported upon its individual roller. With the form of roller shown in said application Serial No. 781,919, it is necessary for the operative, after placing the trident in the creel, to move the yarn carriers laterally until each is supported entirely upon its individual roller.

Another of the objects of the present invention is to provide means whereby the necessity for such manual positioning of the yarn carriers upon the rollers shall be obviated, and whereby, when the section beam to which the cheeses are attached is revolved, the cheese shall move laterally until each is properly located upon its roller.

The invention also relates to the other features of improvement hereinafter set forth.

In the accompanying drawings, Figure 1 is a fragmental view of a trident and a part of the means whereby the trident is supported in the warper creel frame, the yarn masses and yarn carriers being shown in longitudinal central section. The yarn carriers are illustrated in the position which they may at first occupy in the creel. Fig. 2 is a view generally similar to Fig. 1, but showing the yarn carriers as having been moved laterally into operative position upon their respective rollers. Fig. 3 is a fragmental longitudinal sectional view upon a larger scale. Fig. 4 is a fragmental view of one of the trident rollers showing the position of the oil level when the trident is in use at the winder or is being transported to the creel. Fig. 5 is a fragmental view illustrating the construction that enables the cheeses to cross the spaces between the rollers.

In the drawings *a* indicates a cheese consisting of yarn spirally wound upon a tubular core *b*. In the form of cheese core herein shown, the axial opening of the cheese core is defined by inturned end flanges *b*⁴. Within the core is a sleeve *b*⁵ that extends from one flange *b*⁴ to the other and surrounds said flanges.

In the creel the cheeses are rotatably supported upon spindles 1, four cheeses, in the present embodiment, being carried by each spindle. The cheese cores are not mounted directly upon the spindle, but are carried by rollers 2 which are rotatably supported upon the spindle. In the construction herein shown, the roller is formed of sheet metal. Ball bearings are interposed between the

roller and the spindle. While the ball bearings may be of any suitable character, the construction selected for illustration comprises a sleeve 3 which is mounted upon the 5 spindle 1, the ends of said sleeve being expanded to form ball races 4. Each roller 2 comprises inturned flanges 5 which are bent to form ball races 6. Between the ball races 4 and 6 are placed balls 7. Inwardly of the 10 ball races 6, each flange 5 is continued to form an annular lip 8. To lubricate the ball bearings, a small quantity of oil α is placed in each roller 2 before the roller is placed upon the spindle, the oil being introduced 15 through an opening 9 in the sleeve 3. The quantity of oil is such that the level of the oil never touches the sleeve 3 whether the spindle is in horizontal or in vertical position, the level of the oil never reaching the 20 lip 8.

As shown in the drawings, the roller 2 has a generally crowning periphery. The end portions of the roller are tapered to provide surfaces 10 for supporting the bearing flanges b^4 of the cheese core. The remainder of the periphery of the roller is cylindrical. As indicated in Fig. 3, the rollers are relatively close together.

In the construction herein illustrated, the 30 trident comprises a base 12 which may be of wood. The spindle 1 is secured to the base 12 by means of an attaching member 13. Upon the outer end of each spindle is a tubular tip or cap 14 which for convenience 35 in manufacture is made rotatable, said tip being mounted upon a sleeve 15 having an out-turned flange upon its inner end. The sleeves 3 are spaced away from each other and from the attaching member 13 and the 40 tip 14 by means of sleeves 16 having out-turned end flanges that abut the flanges of the sleeves 3 and 15. The series of sleeves 3, 15 and 16 is clamped against the attaching member 13 by means of a nut 17 screwed 45 upon the outer end of the spindle 1.

A spool 18 is rotatably mounted upon each sleeve 16. As shown in Fig. 3, the ends of the rollers 2 are countersunk so as to overhang the spools 18. These spools receive 50 any yarn which may get between the rollers 2 or between said rollers and the attaching member 13 and the tip 14. In case some yarn should become wound upon one of the spools 18, the yarn may be readily unwound 55 therefrom by the operative, since the spool will rotate freely as the yarn is withdrawn.

As heretofore stated, when the tridents are in use at the winder or in transit between the winder and the warper creel, they 60 stand upon their bases 12 with the spindles 1 in upright position. When in such position the cheese cores b on a given spindle rest upon one another. As positioned in the creel the spindles are horizontal. The 65 threads of the cheeses having been connected

to the section beam of the warper, said beam is rotated to wind the threads thereon. Referring now to the cheese core which is nearest the base 12 in Fig. 1: It will be observed that one end of this cheese core rests upon 70 a portion of the trident roller which is smaller in diameter than the portion upon which the other end of the cheese core rests. When the cheeses are rotated by the traction of the section beam, the end of the cheese 75 core which rests upon the roller portion of larger diameter will tend to travel faster than the other end of the cheese core, and hence the cheese is caused to cant, as a result of which the cheese core moves side- 80 wise as it revolves until it has reached a central position upon its roller, when both ends of the cheese core will be resting upon portions of the trident roller of equal diameter. As shown in Fig. 1, each cheese core rests 85 upon different diameters of its own trident roller or upon different diameters of two adjacent rollers, and hence the self-centering action just described takes place with relation to each cheese core. All of the 90 cheese cores are thereby placed out of contact with each other, as represented in Fig. 2.

Referring to Fig. 5: It will be noted that the sleeve b^5 rests upon the cylindrical portion 95 of the roller 2 at the time one of the flanges b^4 is directly over the space between the rollers, so that it is impossible for the flange b^4 to drop low enough to catch on the end of the roller onto which the cheese is 100 moving. Inasmuch as the contacting portions of the cheese core and the trident roller are still of different diameters, the cheese core continues to move endwise until it reaches its proper running position. When 105 the cheese core has traveled to the right a short distance from the position illustrated in Fig. 5, the flange b^4 comes into contact with the tapering surface 10 of its own roller and takes the load off the sleeve b^5 . 110

Referring to the self-oiling feature. When the cheeses are rotated the oil α is spread over the inner periphery of the rollers 2, and when the cheeses are stopped some of the oil creeps over the flanges 5 and 115 the lips 8 and thus enters the bearings. The lips 8 increase the distance through which the oil must creep and thereby reduce to the desired extent the amount of oil that reaches the bearings. The amount of oil 120 that reaches the bearings at any given stoppage is so small that the supply contained in the roller lasts for a long time.

It will be seen that each roller 2, with its sleeve 3 and series of balls 7, constitutes 125 a self-contained roller unit which may be readily placed upon or withdrawn from the spindle 1 when necessary.

I claim as my invention:

1. A creel section having a supporting 130

- base and a spindle extending perpendicularly to the base, a roller on the spindle, ball-bearings between the ends of the roller and the spindle, said roller being chambered to contain oil, the end of said roller adjacent to the base being chambered to form a pocket to contain the oil, the inner wall of said pocket keeping the oil out of the adjacent ball-bearing.
- 10 2. A yarn carrier support having, in combination, a support, a roller mounted on the support, one end of the roller having an inwardly extending flange encircling the support, and a bearing between the roller and the support, said bearing being located outwardly of the inner end of said flange, said end of the roller having an annular chamber to contain oil, said flange serving to keep the free surface of the oil out of contact with the support.
3. A yarn carrier support having, in combination, a sleeve, a roller mounted on the sleeve, one end of the roller having an inwardly extending flange encircling the sleeve, and a bearing between the roller and the sleeve, said end of the roller having an annular chamber to contain oil, said flange serving to keep the free surface of the oil out of contact with the sleeve.
- 30 4. A yarn carrier support having, in combination, a sleeve, the ends of said sleeve being expanded to form ball races, a roller having inturned end flanges which are bent to form ball races, and balls between the ball races on the sleeve and the ball races on the roller, said roller having a chamber to receive lubricant, the sleeve having an opening through which lubricant may be introduced into the chamber.
- 40 5. A yarn carrier support having, in combination, a spindle, a sleeve on the spindle, the ends of said sleeve forming ball races, a roller having inturned end flanges which are bent to form ball races, and balls between the ball races on the sleeve and the ball races on the roller, said roller having a chamber to receive lubricant, the sleeve having an opening through which lubricant may be introduced into the chamber.
- 45 6. A yarn carrier support having, in combination, a spindle, a plurality of sleeves on the spindle, a roller rotatably mounted upon each sleeve, the adjacent ends of the rollers overhanging said sleeve, a spacer between the sleeves, a spool rotatably mounted on the spacer, the ends of the rollers overhanging said spool, and means to clamp the sleeves and the spacer on the spindle.
7. A yarn carrier support having, in combination, a spindle, a plurality of sleeves on the spindle, a roller rotatably mounted upon each sleeve, the adjacent ends of the rollers overhanging said sleeve, a spacer between the sleeves, a spool rotatably mounted on the spacer, and means to secure the sleeves and the spacer on the spindle.
8. A creel section comprising a base having a spindle thereon; and a plurality of rollers on said spindle, each roller being adapted to support a yarn carrier having end bearing flanges, and an interior sleeve of larger interior diameter than said flanges, each roller having end portions of reduced diameter to support the bearing flanges of the yarn carrier, said sleeve resting upon the roller when one of said flanges is above the space between two rollers, so as to hold said flange up out of engagement with the end of the roller.
9. A yarn carrier support having, in combination, a spindle, and a plurality of rollers on said spindle arranged relatively close together, each roller being adapted to support a yarn carrier having end bearing elements, each roller having at its ends annular beveled surfaces on which the bearing elements of the yarn carrier are normally supported.
10. A yarn carrier support having, in combination, a sleeve, ball races at the ends of said sleeve, a roller, ball races carried by the roller, and balls between the ball races on the sleeve and the ball races on the roller, said roller having a chamber to receive lubricant, the sleeve having an opening through which lubricant may be introduced into the chamber.

In testimony whereof I have hereunto set my hand.

BURT A. PETERSON.
